UNITED STATES PATENT OFFICE.

ARTHUR SANTERRE, OF LOS ANGELES, CALIFORNIA.

UPEDGING AND COLLAPSING PORTABLE BED.

Application filed January 26, 1925. Serial No. 4,756.

This invention relates to that type of bed which is folded into a compact form, and is then turned on its side and wheeled into a closet or other storage space. In my invention I provide a novel construction whereby the legs, head and foot members fold closely against the frame of the bed.

An object of my invention is to provide a novel means of securing the head and foot members in the folded position so that the bed clothing and mattress are securely held in position by said head and foot members when the bed is turned up on edge.

Another object is to so form the legs that they may be used to facilitate the up-edging of the bed.

A further object is to provide a bed which is simple in construction, efficient in operation, and inexpensive to manufacture.

Other objects, advantages and features of invention may appear from the accompanying drawing, the subjoined detailed description and the appended claims.

The accompanying drawing illustrates the invention.

Figure 1 is a side elevation of a bed constructed in accordance with this invention and having a mattress thereon and in position for use.

Fig. 2 is a like view on smaller scale showing the bed ready to up-edge with the head and foot boards collapsed and fastened down upon the mattress.

Fig. 3 is a view of the top of the bed after it has been up-edged. A portion of the mattress has been broken away to show the springs beneath.

Fig. 4 is an end view looking from the right of Fig. 3.

Fig. 5 is a view of the opposite side of the bed from that shown in Fig. 3, with the mattress removed.

1 indicates the substantially rectangular frame of my bed, the end rails of which are bent upwardly at approximately right angles to the side rails of the main frame as shown at 2 and 3.

The bed spring 4 may be of any desired type and is suspended between the upturned ends 2 and 3, and is secured to angle members 5 and 6 that are secured to the ends 2 and 3, respectively.

For the sake of convenience I have here illustrated that type of bed spring which has flat steel ribbons 4' secured at one end to the members 6 and which are secured at

their other ends to coil springs 4", which may be secured to the angle member 6.

Legs 7 and 8 are pivoted as at a to each end of the frame 1, and each of the legs is preferably formed in one piece, extending across the frame from side to side thereof and provided with arcuate sides 9—9, and 10—10, respectively, as shown in Figs. 4 and 5 to form rockers for use in turning the bed onto its edge, it is rocked into position with very little effort, by merely up-edging the bed and rolling the same on the arcuate sides 9 and 10 of said legs.

Coil springs 11 and 12 are secured at one end to the legs 7 and 8, respectively, and at their other ends to the angle members 5 and 6, respectively.

These springs 11 and 12 hold the legs in either the open or closed position by swinging to either side of the center of the leg pivots.

Bed ends 13 and 14 are pivoted to the main frame 1 at 15—15 and 16—16, respectively, adjacent the pivots for the legs 7 and 8, and are adapted to fold inwardly upon the bed.

These ends consist of transverse barriers 13', 14', and reaches 13", 14", extending from the ends of said barriers to the pivots; the pivots extending through the reaches adjacent the lower end thereof.

The reaches in the folded position extend obliquely across the bed frame and the bedding supported thereby and when the bed is up-edged, the reaches form stable supports for the up-edged bed, and such supports may be supplemented by anti-friction devices to allow trundling of the up-edged bed.

The bed ends 13 and 14 are spaced from the frame 1 by their pivots 15 and 16 so that the legs 7 and 8 may swing between the frame and the bed ends, and bear against said pivots in the open position. Thus the pivots 15 and 16 act as stops for the legs 7 and 8 in open position of such legs.

The angle members 5 and 6 protrude beyond the edges of the frame 1 and the bed ends 13 and 14 rest thereon when in open position. The bed ends and legs are preferably formed of a single piece of tubing or pipe bent into shape.

Castors 17—17 and 18—18 are mounted on the bed ends 13 and 14 respectively, to provide anti-friction means whereon the bed may be easily moved into a closet or storage room after the bed has been up-edged.

A pair of hooks 19 and 20 are pivotally secured to loops 22 and 23 formed in a wire frame 21 that is connected to the springs 4 on either side thereof. The loops 22, 23 enable the hooks to turn or swing into any desired position, thus making it easier to fasten the hooks to the bed ends.

The hooks 19, 20 engage the bed ends 13 and 14 in the folded position as shown in Fig. 2.

In practice to collapse and store the bed, the ends 13 and 14 are folded upon the mattress 24 and bed clothing that may be supported thereby, and the hooks 19 and 20 hold them firmly in position.

The bed is then rocked over on its side by rolling the same on the arcuate leg sides 9 and 10, thus up-edging the bed, and when in one up-edged position the bed rests on the castors 17, 18.

The legs 7 and 8 are then folded inwardly as shown in Fig. 5, and the bed is ready to be wheeled away. When the bed is up-edged in the other direction it will rest stably upon the diagonally transverse reaches 13", 14".

The operations to open the bed up for use are the reverse of that for collapsing the same.

I claim:

1. A portable bed comprising a frame, legs mounted on each end of said frame, bed ends pivoted to the ends of said frame and adapted to fold inwardly upon the bed; the pivots of said ends being arranged to form stops to prevent the legs from collapsing towards the end of the bed; and springs connected to the legs of the bed and to the bed frame rearwardly of the pivots of the legs so as to yieldingly hold the legs against the stops.

2. A portable bed comprising a bed frame,

legs and a spring, bed ends pivoted to each end of said frame and adapted to fold inwardly upon the bed; a hook frame connected to said spring, loops formed in said hook frame, and hooks mounted in said loops, and adapted to engage the bed ends when said bed ends are moved to closed position.

3. A portable bed comprising a frame having lateral stops at its ends; bed ends in the form of loops having the ends of the loops pivoted to the bed frame between its ends so that the bed ends when swung from each other will come to rest upon the stops and their loops will be upright above the stops; said bed ends being provided at one side of the bed with anti-friction means adapted to support the bed when upturned on one edge; means to hold said bed ends when folded onto the bed so that said anti-friction means will form a stable support for the bed when up-edged; legs formed of loops and pivoted to the bed frame between the pivots of the bed ends and the middle of the frame; springs connected to the loops of the cross bars of the legs and to the ends of the frame and adapted to swing past the pivot centers of the legs as the legs are swung from leg supporting position against the pivots of the bed ends, so that the legs will be held by said springs in bed sustaining position when the legs are unfolded, and will be held in folded position when the legs are folded, for the purpose of providing a compact folded bed adapted to be moved edgewise into a narrow space equal in height to the width of the bed.

In testimony whereof, I have hereunto set my hand at Los Angeles, California, this 21st day of January, 1925.

ARTHUR SANTERRE.
